UNITED STATES PATENT OFFICE.

MOSES JOHNSON, OF COLEBROOK, NEW HAMPSHIRE.

IMPROVEMENT IN INVALID-BEDSTEADS.

Specification forming part of Letters Patent No. 40,413, dated October 27, 1863.

To all whom it may concern:

Be it known that I, MOSES JOHNSON, a resident of Colebrook, in the county of Coos, and State of New Hampshire, have invented an Improved Invalid-Bedstead; and I do hereby declare the same to be fully described in the following specification and represented in the accompanying drawings, of which—

Figure 1 is a top view of it; Fig. 2, a side elevation, Fig. 3 an end elevation, and Fig. 4 a vertical and longitudinal section, of it.

In the construction of this bedstead each of the posts A, is divided crosswise into two parts, a b, the four upper portions, a a a a, being connected together by two longitudinal rails, c c, a head board, d, and a foot-board, e, and so as to constitute a sacking-frame, G. The four lower portions, b b b b, or what may be termed the "leg" parts of the posts, are connected together by two longitudinal and two transverse rails, as seen at f f g g, the longitudinal rails f f being so made as to be capable of supporting the slats or other devices usually employed in bedsteads for sustaining the mattress or bedding. Furthermore, there is applied to each two of the head and foot parts b b of the frame H an auxiliary head or foot board, B C, which is so hinged to them, (viz., as shown at h in Fig. 5, which is a top view of the lower or mattress supporting part or frame H,) as to be capable of being turned up into a vertical position above them, and so as to convert the bottom part, H, into a separate bedstead provided with head and foot boards distinct from the main head and foot boards of the upper or sacking-supporting part of the bedstead. The upper end of each of the lower portions, b b b b, of the posts may be furnished with a mortise, k, to receive a corresponding projection or tenon extending from the sacking-supporting frame or upper portion of the bedstead when placed on the lower or mattress-supporting part. I provide the said sacking-supporting part with an elevator, D, which consists of two parallel bars, l l, a third or connecting bar, n, and a piece of cloth or canvas, P, stretched across them. One end of each of the two bars l l, is hinged to one of the rails c c. Short posts m m arise from the head of the elevator and support a cranked shaft, m², to which the two ends of a rope, n', is fastened, the middle of the said rope being sustained by

a staple, o, fixed in the ceiling of the apartment in which the bedstead may be. By revolving the said shaft the elevator may be raised from a horizontal into an inclined position or may be depressed from the latter, according to circumstances. The sacking further consists of another piece of cloth or canvas, q, which extends across the lower half of the sacking-frame and is carried underneath the part p, and hooked or otherwise connected to a staple, r, fixed in the head-board d. The part q, of the sacking being separate from and extending underneath the part p, not only affords additional support to the latter where the greatest weight of a person is borne by it, but is to close the opening or passage which is intentionally made between the two parts p q, for the purpose of enabling a bed-pan or other vessel to be introduced underneath the excretory parts of an invalid supported on the sacking. The sacking-frame of the bedstead is to be suspended from the ceiling of a room by means of two ropes, r² r², which extend longitudinally underneath it and at their extremities are attached to four staples, s, inserted in the said ceiling. These ropes, in passing from one set of staples to the other, go around a windlass or cranked shaft, F, which is affixed to the head part of the sacking-frame, and is provided with two projecting hooks, t t, arranged as shown in Figs. 1 and 4. By looping each rope on one of the said hooks and rotating the shaft F the sacking frame of the bedstead may be either raised or lowered, according to the direction in which the shaft may be revolved. If only one of the ropes be looped on one of the hooks, the sacking-frame will be tipped laterally during the revolution of the shaft. The object of tipping the sacking-frame laterally is to enable an invalid to be turned in bed to advantage, as when the sacking is tipped gravitation will aid in rolling or turning the patient. In this way, whenever it may be desirable to air or cleanse the sacking he may be rolled and slid off the latter and upon the mattress supported by the lower part of the bedstead. The said lower part or mattress-supporting part of the bedstead is to be provided with casters or rollers to its legs, in order that it may be readily drawn out from underneath or pushed under the sacking-supporter, as circumstances may

require—that is to say, in order that the mattress may be either shaken up or aired, or that a bed-pan or vessel may be applied underneath the excretory parts of the invalid.

The improved bedstead, constructed as described, can readily be converted into two separate bedsteads, as while the upper portion may support a mattress and bedding, another mattress and bedding may be applied to the lower portion, in which case the auxiliary head and foot boards of the lower portion may be turned up relatively thereto, they being turned down when the two portions of the bedstead are used together with an invalid reposing on the sacking and the latter resting on the mattress supported by the lower portion of the bedstead.

I do not claim an invalid-bedstead made with an elevator to raise a person into a recumbent or sitting position.

I claim—

1. The improved invalid-bedstead as made with the divided posts A and the separate

mattress and sacking frames arranged and combined therewith, substantially as specified.

2. In combination with the bedstead so made, the auxiliary head and foot boards B C, applied to the mattress-frame in manner and so as to operate substantially as described.

3. The mode of making and applying the sacking—viz., in two parts, p q, one being applied to the elevator-frame, and the other being fixed to the sacking-frame and extending underneath the elevator D, and hooked to and connected with the head-board d, as and for the purpose specified.

4. The combination of the tipping-hooks tt, or their mechanical equivalents, with the bedstead and their windlass or shaft F, the whole being constructed and so as to operate substantially as described.

MOSES JOHNSON.
